(57) **CLAIM**

The ornamental design for a mold for ice shooting targets, as shown and described.

DESCRIPTION

FIG. 1 is a perspective view of a mold for ice shooting targets showing my new design;

FIG. 2 is a top plan view thereof;

FIG. 3 is a right side elevational view thereof;

FIG. 4 is front elevational view thereof;

FIG. 5 is a rear elevational view thereof;

FIG. 6 is a bottom plan view thereof; and,

FIG. 7 is an enlarged cross sectional view taken along line 7-7 of FIG. 2.

The broken lines associated with the molds are for illustrative purpose only and form no part of the claimed design.
